CLAIM

The ornamental design for a core ball, as shown and described.

DESCRIPTION

FIG. 1 is a right side view of the core ball according to the design of the invention. The left side view is exactly the same as the top view.

FIG. 2 is a front view of the design according to the invention. The rear view of the design is exactly the same as the front view.

FIG. 3 is a top view of the design according to the invention. The bottom view is exactly the same as the top view; and, FIG. 4 is a perspective view of the design according to the invention.

The broken lines in the drawings are to depict portions of the design and form no part of the claim.
